UNITED STATES PATENT OFFICE.

CHARLES STOLP, JR., OF CHICAGO, ILLINOIS, ASSIGNOR TO THE FLINTKOTE COMPANY,
OF BOSTON, MASSACHUSETTS, A CORPORATION OF MASSACHUSETTS.

ROOFING.

Application filed June 14, 1923. Serial No. 645,440.

When roofing of comparatively thin material, such for example as so called asphalt shingles is used, objection is sometimes made that it presents a flat, monotonous, cheap and unsubstantial appearance. In order to overcome this objection it has been proposed to use shingles of different colors mixed in together. One method of doing this has been to mix indiscriminately about equal 10 quantities of shingles of each color, commonly two or three colors being employed, the shingles of various colors being selected at random when laid in the attempt to avoid the production of any distinct pattern in the 15 finished roof. This has not proven satisfactory since this method of laying is so indiscriminate that it results in masses of unbroken color in spots and diagonal runs or horizontal streaks of the same color sometimes of considerable length. The workman laying the shingles is too close to the roof to be able to properly judge the general color effect which he is producing. In order to overcome this serious defect, the roof has 20 sometimes been plotted on paper and colored pieces shifted about thereon until the desired effect has been obtained, whereupon the location of the various colors has been indicated and the roof laid strictly according 25 to the pattern so formed on the paper. This pattern method, it is quite evident, adds largely to the expense of laying the roof and even then the results have not been uniformly satisfactory.

30 One of the reasons for the unsatisfactory effect from an artistic standpoint has been discovered to be in the proportions of colors heretofore used. The appearance of the roof, it is found, may be improved by using a predominance of one color, using a smaller proportion of a blending color and a still smaller proportion of a contrasting color.

35 This invention contemplates the use of colors so proportioned, and in order that they may be properly distributed provides a method of packing the shingles into bundles with the shingles of the several colors distributed therein according to a predeter-

mined somewhat irregular arrangement so that the shingles can be laid in their order 50 of packing as they are successively presented to the workman or they may be dumped on the roof and taken as they come without danger of splotches of color or long runs diagonally or laterally of the roof being 55 formed, and yet without the formation of any distinctive pattern, the shingles of the various colors being distributed substantially uniformly throughout.

For a more complete understanding of this 60 invention, reference may be had to the accompanying drawings in which

Figure 1 is a plan of a roof constructed according to this invention, the different colors being diagrammatically illustrated. 65

Figure 2 is a similar view of a roof laid according to the former methods showing certain objectionable characteristics which it is designed to obviate.

Figure 3 shows in perspective a shingle 70 package with certain shingles elevated to show the arrangement of the various colors.

For the purposes of illustration a roof in which the color red predominates has been chosen, the blending color used in much 75 smaller proportion being blue-black, and the contrasting color being green, these three colors being colors commonly employed in the so called asphalt shingles and being produced by the use of slate coating of these several colors. In case a predominant blue-black roof is desired, the green may be used as the blending color and the red as the contrasting color, while in case the green is desired to be predominant the blue-black may 80 be the blending color and the red the contrasting color.

It is desirable that the roof be laid with 85 a substantially uniform mixture of the colors, but it is also desirable that they be 90 irregularly laid to prevent the formation of any distinctive pattern but with insufficient irregularity in the color effect to be displeasing from the artistic standpoint. In order to insure the laying of the shingles in 95 substantially the desired manner they may

be packed in bundles each of which presents the proper proportion of the various colors and arranged in a predetermined somewhat irregular manner. For example, the shingles may be arranged according to the following table:

3 Red	1 Green
2 Blue-black	2 Blue-black
10 1 Green	3 Red
3 Red	2 Blue-black
1 Blue-black	2 Green
2 Red	1 Blue-black
2 Blue-black	3 Red
3 Red	2 Blue-black
15 2 Green	3 Red
3 Red	2 Green
2 Blue-black	3 Red
3 Red	2 Blue-black
1 Blue-black	3 Red
20 3 Red	2 Blue-black
2 Blue-black	2 Blue-black
3 Red	3 Red
1 Blue-black	2 Blue-black
25 3 Red	3 Red
2 Blue-black	1 Green
3 Red	2 Blue-black
2 Blue-black	3 Red
3 Red	1 Blue-black
1 Blue-black	3 Red
2 Green	1 Blue-black
3 Red	3 Red
2 Blue-black	1 Blue-black
30 3 Red	1 Blue-black
	1 Green

This provides 62 red shingles, 32 blue-black shingles and 12 green shingles. This sequence of colors may be repeated four times so as to present 424 shingles to the bundle and with this method of packing and with the usual shape and size of shingles, four such bundles will complete a "square".

40 The shingles may be laid in courses directly as taken from the bundles, or the bundles may be spread out on the roof and the shingles taken at random with the assurance that the same general effect will be produced.

45 In Figure 1 is illustrated the general effect of a roof constructed in this manner, the red being predominant and indicated by vertical shading, the blue-black indicated by cross diagonal shading and the green by a single diagonal shading. It will be seen that there are no long runs or splotches of color in the roof and at the same time there is no distinct pattern.

In Figure 2 is illustrated the appearance 55 where packages with the same proportion of the colors have been employed and the shingles laid at random. For example at *a* and *b* are indicated two areas of solid color which are so substantial in size as to present a splotched effect while there are also produced long runs of a single color in diagonal or lateral lines such as shown at *c* and *d*. To the workman laying the roof these effects, detrimental from the artistic

standpoint, would not be readily apparent 65 but from a distance the inartistic effect of the roof would be readily apparent.

While this invention has been described with reference to roofs, it should be evident that siding might be laid in the same manner, if desired, and the term "roof" in the 70 claims is therefore intended to include analogous constructions.

Having thus described an embodiment of this invention it should be evident to those 75 skilled in the art that many changes and modifications may be made therein without departing from its spirit or scope as defined by the appended claims.

I claim:

1. A shingle package comprising shingles of different colors arranged in a predetermined irregular color sequence, whereby such shingles may be laid with facility in such sequence on a roof without forming a distinctive pattern.

2. A shingle package comprising shingles of different colors, the shingles of each color being distributed substantially uniformly throughout the package, whereby such shingles may be laid on a roof as presented in the package to produce a substantially uniform color distribution thereover.

3. A shingle package comprising shingles of different colors, the shingles of each color being distributed substantially uniformly throughout the package and the shingles of the several colors being present in unequal proportion, whereby such shingles may be laid on a roof as presented in the package to produce a substantially uniform color distribution thereover, but without forming a distinctive pattern.

4. A shingle package comprising a relatively large number of shingles of one color, a smaller number of shingles of another color, and a still smaller number of shingles of a third color, the shingles of each color being substantially uniformly distributed throughout the package, whereby such shingles may be laid on a roof as presented in the package to produce a substantially uniform color distribution thereover.

5. A shingle package comprising a relatively large number of shingles of one color, a smaller number of shingles of another color, and a still smaller number of shingles of a third color, the shingles of each color being substantially uniformly distributed throughout the package and in a predetermined irregular sequence, whereby such shingles may be laid on a roof as presented in the package to produce a substantially uniform color distribution thereover, but without forming a distinctive pattern.

6. A shingle package comprising shingles of different colors, there being a plurality of shingles of each color, the shingles being

arranged within the package in the sequence in which they are to be individually applied on a roof the shingles will have a color distribution thereover which is uniform but of irregular pattern. 10

7. A shingle package comprising shingles of different colors, the shingles being arranged in the package in a definite color sequence such that when successively applied on a roof the shingles will have a color distribution thereover which is uniform but of irregular pattern. 10

In testimony whereof I have affixed my signature.

CHARLES STOLP, JR.
